Patented Dec. 22, 1914.

UNPATENTED STEALING PATENT OFFICE.

WILLIAM F. SCHWERER, OF SHEPPARDS, VIRGINIA.

RAIL JOINT AND CHAIR.

1,229,163.

Specification of Letters Patent. Patented Dec. 20, 1914.

Application filed September 21, 1914. Serial No. 562,743.

To all whom it may concern:

Be it known that I, WILLIAM F. SCHWERER, a citizen of the United States, residing at Sheppards, in the county of Buckingham, 5 and State of Virginia, have invented certain new and useful improvements in Rail Joints and Chairs, of which the following is a specification, reference being had to the accompanying drawings.

10 This invention relates to new and useful improvements in rail joints and more particularly to a combined rail joint and supporting chair therefor, the main object of the present invention being the provision of 15 a rail joint having a novel supporting chair therefor, wherein the parts of the joint are securely held against lateral and longitudinal movement.

Another object of the present invention is 20 the provision of a device of the above character which will possess advantages in points of efficiency and durability, is inexpensive to manufacture and, at the same time, is simple in construction and operation.

25 With the above and other objects in view, the invention consists in the novel features of construction, combination and arrangement of parts as will be hereinafter referred to and more particularly pointed out in the 30 specification and claims.

In the accompanying drawing forming a part of this application, Figure 1 is a top plan view of a rail joint and chair constructed in accordance with my invention. 35 Fig. 2 is a side elevation. Fig. 3 is a detail perspective view illustrating the joint in its detached position; and Fig. 4 is a transverse sectional view taken on the line 4-4, Fig. 2.

Referring more particularly to the drawing, 40 Fig. 1 indicates the ties, upon which my improved chair is mounted, the chair in general being indicated by the numeral 2. The chair which is generally indicated by the numeral 2 is formed of a body plate, the 45 main portion of which is indicated by the numeral 3 and is adapted to rest upon the ties 1, as illustrated in the accompanying drawing and one edge thereof is bent upon itself, as shown at 4, the bent portion thereof 50 of being mounted upon the body plate 3 and the extreme outer edge of the over-turned edge portion is bent upon itself to form a retaining flange 5, adapted for engagement

over the outer base flange of the rails, which in the accompanying drawing are generally indicated by the numeral 6.

The rail joint which consists of the rail ends 7 and 8, and the central connecting member 9, is adapted to be mounted upon the chair 2 and held in position in a manner which will be hereinafter more fully set forth. The rail ends 7 and 8 are provided at their lower edges with outwardly projecting tongues 10, the lower faces of which are flush with the bottom rails and the central member 9 is provided upon each end and at its lower edge with the inwardly projecting recesses 11 adapted to receive the tongues 10 of the rail ends 7 and 8, to securely hold the rail ends against lateral movement with respect to the ties.

In securing the rail joint in position upon my improved chair, the rail ends are connected together by means of the central arch connecting member 9, and then placed in position upon the outer face of the portion 12, the outer edges of the base flanges of the rail ends and the portion 9 engaging beneath the over-turned flange 5 whereby to prevent outward spreading movement of the rails. After the base flanges have been fitted beneath the over-turned flange 5, securing spikes 13 are driven into the ties 1, through openings 14 formed in the chair 2, for the reception of these spikes, it being understood that the over-hanging heads of the spikes will engage over the inner edges of the base flanges of the rails, so as to rigidly retain them against spreading movement upon the chair. The chair 2 is also securely held in position by securing spikes 15 which are driven through the same at a point removed from the outer edge thereof.

From the above description taken in connection with the accompanying drawing, it will be readily apparent that I have provided a simple and durable rail joint and supporting chair therefor, the chair of which is extremely simple in construction, consisting of a single plate of material and the main portion of which is secured transversely across the top of the ties. The device, as herein illustrated, includes the central portion and the rail ends which are engaged with the joint in such a manner as to securely prevent any lateral movement of

either of the rail ends. The device, as herein shown and described can be quickly and readily assembled and placed in position upon the cross ties and should it be desired to remove a broken rail, the inner securing spikes which are generally indicated by the numeral 13 can be removed, and the ends of the rails, together with the central portion 9 can be pulled from beneath the overhanging flange 5, so as to permit the central portion 9 to be drawn upwardly to disengage the same from the tongues 10. The broken rail can then be moved longitudinally to disengage its other end. My device as a whole is extremely simple in construction and can be manufactured and placed upon the market at a comparatively low cost.

While I have shown and described the preferred form of my invention, it will be obvious that various changes in the details of construction and in the proportions may be resorted to for successfully carrying my invention into practice, without sacrificing any of the novel features or departing from

the scope of the invention, as defined by the appended claims.

Having thus described this invention, what I claim is:—

1. A device of the class described including a rail joint and chair therefor, said chair including a plate having one edge bent upon itself and the inner edge of the over-turned portion being bent upon itself to provide an overhanging retaining flange. 30

2. The combination with a rail joint including rail ends, tongues formed upon said rail ends, a central member having recesses formed at each end thereof to receive said tongues, of a chair including a body plate 40 having one edge bent upon itself and an over-turned engaging flange formed at the inner edge of the upper portion of the chair, as and for the purpose set forth. 35

In testimony whereof I hereunto affix my signature in the presence of two witnesses.

WILLIAM F. SCHERER.

Witnesses:

JOHN RETHGEE,
RICHARD B. WOODAL.
